(57) **CLAIM**

The ornamental design for a storage chest litter box holder, as shown and described.

DESCRIPTION

FIG. 1 is a perspective view of the storage chest litter box holder, showing our new design;

FIG. 2 is a front elevational view thereof;

FIG. 3 is a left side elevational view thereof;

FIG. 4 is a right side elevational view thereof;

FIG. 5 is a back elevational view thereof;

FIG. 6 is a top plan view thereof; and,

FIG. 7 is a bottom view of the storage chest litter box holder thereof.

The broken lines in FIG. 1-3 are shown for illustrative purposes only and forms no part of the claimed design.

This product hides the litter pan in an elegant piece of furniture. Because it looks like a hand-crafted wooden storage chest, this product is able to assist cat owners in maintaining a stylish and elegant home without sacrificing care and comfort for their pets.
